(57) **CLAIM**

The ornamental design for an inoculator, as shown and described.

DESCRIPTION

FIG. 1 is a front, top, and left-side perspective view of an inoculator, showing the new design;

FIG. 2 is a front, bottom, and right-side perspective view of the inoculator;

FIG. 3 is a left-side view thereof;

FIG. 4 is a right-side view thereof;

FIG. 5 is a top view thereof;

FIG. 6 is a bottom view thereof;

FIG. 7 is a front view thereof;

FIG. 8 is a back view thereof; and,

FIG. 9 is another front, top, and left-side perspective view of the inoculator, showing the inoculator in use.

The broken lines in FIG. 9 are for the purpose of illustrating environmental structure and form no part of the claimed design.
